TAPE-REEL STORAGE CASE

Karl D. Kryter, Los Altos, Calif., assignor to Acousis Company, Los Altos, Calif.

Filed Dec. 29, 1972, Ser. No. 319,892

Term of patent 14 years

Int. Cl. D3—99

U.S. Cl. D87—1 D

Fig. 2.

Fig. 1.

Fig. 3.

Fig. 4.

FIG. 1 is a front elevation of a tape-reel storage case showing my new design, the rear elevation being the same;

FIG. 2 is an end elevational view which is the same for both ends;

FIG. 3 is a top elevational view; and

FIG. 4 is a bottom plan view.

I claim:

The ornamental design for a tape-reel storage case, as shown and described.
